UNITED STATES PATENT OFFICE.

DAVID A. ANDERSON, OF FARIBAULT, MINNESOTA, ASSIGNOR TO FARIBAULT MACHINE SHOP & FOUNDRY CO., OF FARIBAULT, MINNESOTA.

DRIVING TOOL.

Application filed June 14, 1924. Serial No. 720,029.

To all whom it may concern:

Be it known that I, DAVID A. ANDERSON, a citizen of the United States, residing at Faribault, in the county of Rice and State of Minnesota, have invented certain new and useful Improvements in Driving Tools; and I do hereby declare the following to be a full, clear, and exact description of the invention, such as will enable others skilled in the art to which it appertains to make and use the same.

My invention provides an extremely simple and highly efficient driving tool particularly adapted for use in driving to or from place tubular wrist pins and bushings, but adapted for many other purposes, as will hereinafter more fully appear. Because of its most important uses, the tool may be properly designated as a wrist pin and bushing driver or drift. For interchangeable application to the projecting end of the driving stem, I provide a plurality of different kinds of tools.

In the accompanying drawings, which illustrate the invention, like characters indicate like parts throughout the several views.

Referring to the drawings:

Fig. 1 is a view chiefly in axial section but with some parts in full plan, showing the improved driving tool;

Fig. 2 is a detail in plan with some parts sectioned, showing a shackle bolt driving tool;

Fig. 3 is a detail view in plan showing a spring-expanding blade;

Fig. 4 is an edge elevation of the blade shown in Fig. 3;

Fig. 5 is a plan view of a nail punch; and

Fig. 6 is an edge elevation of said nail punch.

The driving stem of the tool is preferably a steel rod 7 provided with an outer end 8 reduced for insertion into any one of the interchangeable tools hereinafter described and preferably provided with outwardly spring-pressed clutch-acting balls or elements 9. The hammer-acting hand piece 10 is a heavy tubular structure, either of cast metal or tool steel, closed at one end and provided at its open end with a slightly tapered bushing 11 adapted to be firmly held in place by friction when driven inward. The driving stem 7 works axially through the bushing 11 and, within the

hand piece, is provided with a rigidly secured collar 12 that quite closely fits the bore of the hand piece but slides freely therein.

The tool 13 shown in Fig. 1 is especially adapted for driving bushings to place or for removing the same, and, hence, is provided with a conical point and with an axial bore that adapts it to be telescoped onto the reduced end 8 of the driving stem 7 and there to be frictionally held by the spring-pressed clutch balls 9.

The tool 14 shown in Fig. 2 is especially adapted for driving out shackle bolts and, hence, is of quite small diameter and quite long and is formed at its bolt-engaging end with a conical point 15 and at its other end 70 with a head 16, which latter has a bore 17 adapting it to be telescoped onto the reduced end 8 of the driving stem 7.

The spring-spreading blade 18 shown in Figs. 3 and 4, at one end, has a sharp edge 75 and at its other end is formed with a socket 19 that is adapted to be telescoped onto the reduced end 8 of the driving stem. The nail punch 20 shown in Figs. 5 and 6 is provided at one end with a socket 21, adapted 80 to be telescoped onto the reduced end 8 of the driving stem.

The use of the various interchangeable tools noted will be obvious. Of course, the tool proper will be placed against the object to be driven or displaced, and the operator will usually hold the said tool in position by gripping the outer end of the driving stem 7 and holding the same against axial movements while the heavy hammer-acting handle 10 is reciprocated and driven against the other end of said stem. In the use of this tool, bushings, shackle bolts and the like may be driven out or driven in under tight fit without damaging the same, and other work may be similarly performed. When it is desired to remove the stem 7 from the tubular hand piece, it is only necessary to reciprocate the tool so as to cause the collar 12 of the stem 7 to strike against the bushing. The bushing can be easily replaced by pressure or slight tapping on the outer end thereof.

What I claim is:

A driving tool comprising a hollow heavy hammer-acting handle having an integral striking surface closing one end thereof and having an annular plug applied in its

other end, a stem working axially through said annular plug and provided within said handle with a rigidly secured striking collar working freely within said handle for movement in both direction and engageable with the inner end of said annular plug, the inner end of said stem projecting beyond

said collar and being arranged to strike the integral end of said handle, and a tool applied to the outer end of said stem. 10

In testimony whereof I affix my signature.

DAVID A. ANDERSON.
